(57) **CLAIM**

The ornamental design for a drip catcher cuff, as shown and described.

DESCRIPTION

FIG. 1 is a front top perspective view of the drip catcher cuff of the present invention;

FIG. 2 is a front elevational view of the drip catcher cuff shown in FIG. 1;

FIG. 3 is a rear elevational view of the drip catcher cuff shown in FIG. 1;

FIG. 4 is a left side elevational view of the drip catcher cuff shown in FIG. 1;

FIG. 5 is a right side elevational view of the drip catcher cuff shown in FIG. 1;

FIG. 6 is a top plan view of the drip catcher cuff shown in FIG. 1;

FIG. 7 is a bottom plan view of the drip catcher cuff shown in FIG. 1; and,

FIG. 8 is a top perspective view of the drip catcher cuff shown in FIG. 1 in use being worn on a limb.

Stippling and/or contour lines are included in the various views, for example, FIG. 1-8, to depict surface curvature, flatness, or other shapes. The broken line of a limb in FIG. 8, illustratively depicts exemplary in-use elements that form no part of the design claim but are included to show the invention in context.
